Application December 13, 1934, Serial No. 757,319

3 Claims. (Cl. 87—6)

My invention relates to treatment with solvents for such purposes as cleaning and degreasing, and to the use of volatile solvents. It is especially adaptable and useful for cleaning 5 metal parts or objects preparatory to electroplating, enamelling, painting, and other finishing operations. Various solvents whose vapors are heavier than air may be used, such as benzine, benzol, and chlorinated solvents like carbon 10 tetrachloride, trichloromethane, tetrachloromethane, dichlorethane, tetrachlorethane, trichlorethylene, and tetrachlorethylene, whose vapors are uninflammable. The work may be 15 treated with the liquid solvent or with the solvent vapor, or both, and in many cases, treatment in boiling liquid solvent is desirable. In suitable forms of embodiment, such as herein-after described, my invention affords a compact 20 and efficient machine, semi-automatic in operation, wherein large quantities of work can be rapidly, thoroughly, and economically cleaned, with small labor costs and little loss of solvent. Various other features and advantages of the 25 invention will appear from the description hereinafter of species thereof, and from the drawings.

In the drawings, Fig. I is a side elevation of one preferred form of apparatus suitable for the purposes of my invention, with a diagram of certain electric circuits.

Fig. II is a corresponding diagram of a conveyor system shown in Fig. I, with the casing or solvent vessel of Fig. I in vertical longitudinal section.

Fig. III is a view, with various parts in section, taken as indicated by the line and arrows III—III in Fig. I.

Fig. IV is a fragmentary view, with part of the apparatus in transverse section, taken as indicated by the line and arrows IV—IV in Fig. I.

Fig. V is a fragmentary view taken as indicated by the line and arrows V—V in Fig. I, with part of the wall of the apparatus broken away and removed.

Fig. VI is a plan view of the piping connections of the apparatus.

The apparatus shown in Figs. I, II and III comprises a sheet metal treating vessel or enclosure 10 that contains the solvent, whether 50 used as liquid or as vapor, and is closed to exclude air and retain any solvent vapor that may be present,—purposely or incidentally,—but is preferably open upward for the introduction and removal of work. For passing the work in and 55 out of or through the vessel 10 for treatment,

there may be a conveyor system 11, shown in the drawings as of an endless chain-and-sprocket type. The enclosure or vessel 10 and most of the sprockets or other guide and driving means of the conveyor system 11 are mounted and supported on or in a (metal) framework 12, sufficiently open to allow passage of the work (not shown) between its sides. Over the vessel 10 there may be a lid or cover 13 somewhat shorter than the vessel; so as to leave openings at its 10 ends for the passage of the conveyor, and preferably removable: it is shown as having the form of a shallow pan, inverted.

To avoid confusion, only a single work carrier 14 is shown in Fig. I; but in practice, there 15 will preferably be a number of such carriers 14, at suitable intervals along the conveyor chains, as shown in Fig. II and explained hereinafter. As shown in Figs. I and III, the work carrier 14 comprises a foraminous or openwork work- 20 support or shelf 15 suspended by rods 16, 16 at its ends. The rods 16, 16 are preferably of such length that at the low points of the conveyor path, the shelf 15 will be rather close above the corresponding portion of the bottom of the ves- 25 sel 10, as shown in Figs. I, II, and III.

In general, work is treated with liquid or porous solvent (or both) in the lower part of the vessel 10, while its upper portion serves mainly to prevent or minimize loss of solvent 30 vapor from the vessel. For when the solvent employed is highly volatile like gasoline or benzine, or when the work is immersed in the solvent while itself hot or warm, or when the solvent is used hot or even boiled during use, or 35 when the solvent is purposely used in the vapor state,—in all such cases, solvent vapor will be present, and will tend to accumulate to the point of overflowing over the upper edge of the vessel 10. As shown in Figs. I and II, the vessel 10 has 40 a plurality of distinct treating compartments or wells 20, 21, 22 separated by “dams” consisting of partition-like upward folds 23, 24 of the sheet metal forming the bottom of the vessel. In these several wells 20, 21, 22, articles or work may be 45 more or less differently treated with the solvent.

As here shown, also, the well 20 is provided with heating means, such as a steam coil 25 near its bottom, for heating, vaporizing, or even boiling a body or bath of the liquid solvent retained in 50 said well. The escape of solvent vapor thus or otherwise present in the vessel 10 may be prevented by suitable upward extension of its walls as at 26, and by condensation of the vapor from 55 this upper part of the vessel. The cover 13,

when used, also serves to minimize the unavoidable minor losses of solvent vapor, by preventing drafts of air above the vessel 10 from causing eddies in the latter and thus drawing or 5 forcing solvent vapor up over the edges of the vessel.

Condensation of vapor from the upper portion 26 of the vessel 10 may be effected by the external atmospheric cooling of the walls at 26, if 10 they are of sufficient height; though generally it is preferable to supplement or (largely) replace atmospheric cooling with more effective cooling means, so that the vessel 10 need not be so deep as mere atmospheric cooling would require. The 15 particular type and arrangement of cooling means—whether internal or external, and whether on one side, two or more sides, or all around the vessel 10—is broadly immaterial, except that the greater the extent of the cooling 20 means perimetrically of the vessel, the less its extent vertically need be to give adequate exposed cooling area. The solvent vapor, being heavier than air, will always flow by gravity toward the region or area where it is most rapidly cooled 25 and condensed,—just as if there were an actual outlet for the vapor at such region.

As shown in Figs. I, II, and III, the upper vessel walls 26 are (externally) water-jacketed at 27 on three sides, above the wells 21 and 22,—30 thus causing a continual flow of the solvent vapor rising from well 20 over well 21 into and across through well 22, where a body or bath of solvent vapor accumulates and is retained. The jacket 27 has an inlet 27a for water or other 35 cooling medium at its lower corner on one side of the vessel 10 and an outlet 27b at its upper corner on the other side of the vessel 10. Part of the pure liquid solvent condensed by the cooling jacket 27 on the vessel walls 26 runs down 40 directly into the well 21, where a body or bath of this liquid solvent is accumulated and retained. The rest of the condensate runs down into a trough 28 extending around three sides of well 22 and over dam 24 to a point above well 45 21. At the opposite sides of the vessel 10, the trough 28 slopes downward toward well 21, and from the trough ends drain pipes 29 deliver the 50 pure condensate near the bottom of well 21. Thus the condensate is diverted to well 21 to the exclusion of well 22. Such vapor as condenses on walls 26 directly above well 20 (by atmospheric cooling) runs down into well 20. As 55 shown, wells 21 and 22 are both unheated.

Thus, it will be seen, well 20 normally contains (boiling) hot solvent about up to the level 55 shown in Fig. II; well 21 normally contains the relatively cool and pure condensed solvent to the level determined by the lower of dams 23 and 24 (preferably the latter), as shown; and well 60 22 normally contains solvent vapor with which it is kept charged, as already explained. The condensate from trough 28 introduced through pipe 28 into the bottom of well 21 agitates this whole well 21, so that lint and other dirt loosened by the pure solvent in this well is flushed or washed off the work more thoroughly. As 65 here shown, the tops of dams 23 and 24 slope rather gently upward away from well 21 toward their crests, to facilitate overflow of drops of 70 water floating at the surface of the solvent in well 21. Such drops of water float partly submerged in the solvent in well 21,—something like ice-bergs,—and the comparatively gentle slope of the tops of the dams 23, 24 allows the 75 overflowing solvent to roll these water-drops up the

slope and over the crest of whichever dam is the lower. But for this, water condensing from the superjacent air in contact with the vapor in the vessel 10 would accumulate into a layer covering the liquid solvent in the well 21, and this 5 water would tend to waterspot the work treated in the well 21.

Preferably, the distances or intervals along the conveyor chains from one work carrier 14 to the next correspond to the distances or intervals of travel of the work carriers along the conveyor path between their adjacent treating positions or low points in the series of wells 20, 21, 22. These distances or intervals are preferably the same for the treating positions in wells 21 15 and 22 as for those in wells 20 and 21.

As shown in Figs. I and III, the framework 12 comprises separable lower and upper sections 30, 31, associated, respectively, with the vessel 10 and the cover 13. These sections 30, 31 are separable at a plane corresponding approximately to the upper edges of the vessel 10, where they have longitudinals 32, 33 of angle section, respectively.

The lower frame section 30 comprises a rectangular base 34 constructed of longitudinal and transverse channel members, and side frames attached thereto and including uprights 35 connected at their upper ends by the longitudinals 32, and intermediately by longitudinals 36 of angle section. The side walls of the vessel 10 may be secured to the longitudinals 32, 36, and its bottom may be secured to the base 34, which is shown provided with a saddle structure 37 secured thereon and engaging against the side 35 wall of well 20, under the bottom of well 21, and under the bottom and against the side of well 22. This structure 37 comprises longitudinal angle bar frames under the sides of vessel 10, and transverse webs 38 under the corners of well 21. 40 At their top and intermediate longitudinals 32 and 36, the side frames of section 30 are interconnected by transverse angle bar members 39.

The upper frame section 31 comprises a rectangular top structure 41 constructed of longitudinal and transverse channel members, and side frames attached thereto and including uprights 42 and 43 (the former corresponding to the lower uprights 35) connected at their lower ends by the longitudinals 33. The sides of the 50 cover 13 are shown secured to the longitudinals 33. At the longitudinals 33, the side frames of section 30 are interconnected by transverse angle bar members 44. To the longitudinals 33 are secured vertical bars 45, 46, 47 which extend 55 down into the vessel 10 and carry (sprocket) guide means for the conveyor system 11.

The conveyor system 11 comprises a pair of endless sprocket chains 48, 48 suitably spaced from one another and travelling over a closed 60 course that is determined by guide means mounted on the frame structure 12, and mainly on its upper section 31. The conveyor chain guide means includes a number of relatively small (sprocket) wheels 50 mounted on spindles carried by brackets or bosses 51 affixed to the inner sides of the members of the upper side frames, including the cover 13 and the bars 45, 46, 47, and to brackets (hereinafter described) attached to the top structure 41. Thus the space between 65 the conveyor chains 48, 48 is almost everywhere left open for the passage and swinging of the work and the work carriers 14. Besides four pairs of the (sprocket) wheels 50 whose bracket bosses 51 are mounted directly on the longitudi- 70 75 85 90 95 98 99 100

nals of the top structure 41, there are two pairs of such guide wheels 50 whose brackets 51 are mounted on the inner sides of bracket plates 52, 52 upstanding from the (left-hand) ends of the 5 top longitudinals and of bracket plates 53, 53 depending from said longitudinals near their right-hand ends. An additional pair of the 10 guide wheels 50 have their bracket bosses 51 mounted on brackets 54 upstanding from the top longitudinals and adjustable in ways 55 extending lengthwise of said longitudinals, by means of "endless" adjusting screws 56 suitably mounted on or adjacent said ways. These adjustable brackets 54, 54 serve as "take ups" for independently adjusting the two chains 48, 48 to the desired degree of tautness or slackness. For sustaining the long uppermost chain runs between the guide wheels of the brackets 52 and 54, suitable chain ways or guides 57 may be provided, 20 mounted on the top structure 41 by means of angle brackets 58, as shown in Figs. I and III.

There are also pairs of large sprockets 59, 60 on transverse shafts 61, 62 which are mounted in bearing brackets 63 projecting outward from the 25 lower uprights 35 at each end of the lower frame section 30. These sprockets 59, 60 are so located relative to the path of travel of the work and the work carriers 14 that the shafts 61, 62 do not interfere with them. The upper portions 64 of 30 the shaft bearing brackets 63 are removable, so that the shafts 61, 62 and their sprockets 59, 60 can easily be released and removed. This allows the whole conveyor system 11 to be lifted out of or away from the vessel 10 and the lower frame 35 section 30, along with the cover 13 and the upper frame section 31,—which may normally be secured to the lower section 30 by bolts (not shown) through their engaging members, or in any other suitable way. The conveyor system 11 may conveniently be driven by an (electric) motor 65 40 mounted on transverse angle bar members 66, 66 interconnecting the horizontals 36, through a speed reduction gearing 67 and a chain and sprocket drive 68 to a sprocket wheel 69 on the 45 outer end of the sprocket shaft 62, outside the corresponding bearing bracket 63.

Preferably, the travel of the conveyor system 11 is intermittent, with stationary periods while the carriers 14 are in the wells 20, 21, 22. Such 50 intermittent operation of the conveyor system 11 may be produced automatically, or semi-automatically, as preferred, by suitable control of the electric supply circuit 70 of the conveyor motor 65 by the conveyor 11 itself. As shown, the conveyor 11 is provided with a cam device 71 for each carrier 14, attached to one of the sprocket chains 48 at the carrier 14 (or in suitable position relative thereto), and the motor supply circuit 70 includes a self-closing cutout or "limit" switch 72 (shown as mounted on the chain guide 57) adapted to be wiped and opened by each cam 71,—thus stopping the motor 65 and the conveyor 11 each time a cam acts on the switch 72. This 55 cutout switch 72 comprises a blade 73 pivoted at 74 and normally held against the contacts 75, 75 (so as to close the circuit 70), by a leaf spring 76. There is also a (manual or push-button) switch 77 connected in parallel with the cutout switch 72, and thus adapted to close the circuit 70 independently of the switch 72,—but preferably 60 self-opening as under the action of a spring 78.

The switch 72 always stops the motor 65 and the conveyor 11 with three successive carriers 14 in treating position in the wells 20, 21, 22. When 65 the resulting dwell of these carriers 14 in the

wells 20, 21, 22 has sufficed for the proper treatment of the work carried by them, the operator closes the switch 77 and holds it closed awhile, thus keeping the motor 65 and conveyor 11 in operation until the cam 71 which last opened the 5 switch 72 has cleared its blade 73 and allowed it to close across the contacts 75, 75 and so complete the motor circuit 70 independently of the switch 77; whereupon the operator may release the switch 77 and allow it to open. The conveyor 11 will then continue in operation until another cam 71 has reopened the switch 72, thus again automatically stopping the conveyor with carriers 14 in the wells 20, 21, 22.

For handling liquid solvent and transferring it 15 from one part of the apparatus to another, as may be required, there is shown a system including a (rotary, centrifugal) pump 80 with a suction line 81 having connections to the bottoms of the wells 20, 21 and 22 controlled by suitable valves 82, 83, 20 84, and a delivery line 85 having connections to or above the upper parts of said wells (above their normal liquid levels in ordinary operation) controlled by valves 86, 87, 88, and also an external discharge connection controlled by a valve 89. 25 The pump 80 may be driven by an (electric) motor 90 directly connected thereto, and mounted, along with the pump, on transverse angle bar members 91 (Figs. I and IV) interconnecting the longitudinal members of the base. By means of 30 the pump 80 and its connections above described, liquid solvent can be transferred from any one of the wells 20, 21, 22 to any other, or discharged from any or all of said wells, as may be desired. Preferably the capacities of the wells 20, 21, 22 35 are such that any two of them can hold all the solvent used in the apparatus.

In ordinary operation, any liquid solvent overflowing from well 21 over dam 24 into well 22 may be periodically drawn out, so as to keep down the 40 liquid in well 22 to the level shown in Fig. II, and preferably returned to well 20. As a means for doing this automatically by appropriate operation of pump 80, there is shown (Figs. I and V) an (electric) float switch 93 connected to well 22 45 and responsive to the liquid level therein, for controlling the supply of (electric) power to motor 90: i. e., the switch 93 closes when its float is in the full-line position of Fig. V, and opens when the float is in the dotted position. For this purpose, valves 84 and 86 may be opened and an (electric) switch 94 in the motor supply circuit 50 95 may be thrown into the full line position of Fig. I, so as to interpose float switch 93 between the motor 90 and the system 95. When it is desired to use pump 80 in any other way, switch 94 may be thrown into the dotted position of Fig. I, so as to cut out float switch 93 and connect motor 90 directly into the system 95. For any other position of switch 93, motor 90 and pump 60 65 80 will be cut out of operation.

While various modes of operation and use of the apparatus will be apparent from the foregoing description, one preferred mode of operation is as follows:

The wells 20 and 21 having been initially filled with pure liquid solvent such as trichlorethylene about to the levels shown in Fig. II, and steam being supplied to the coil 25, the solvent in well 20 may be heated up to any temperature desired 70 for treating the work, and even kept boiling. Vapor rising from the solvent in well 20 will rise above dams 23, 24 and spread or flow toward the right (by gravity) into well 22, displacing the (lighter) air. Water (or other cooling medium) 75

will be circulated through the jacket 27. As the accumulating vapor in the upper portion 28 of the vessel reaches the cool area produced by the jacket 27, it will begin to condense, and will thus be prevented from rising more than about mid-height of this condenser 27, and, a fortiori, from overflowing or escaping from the open vessel 10, —since the vapor is heavier than air. In other words, the condenser at 27 will draw and keep down the vapor level well below the top of the vessel 10 and the cover 13.

The endless conveyor system 12, driven by the motor 65, will travel in a closed course including upright loops of approach and recession down around the large (sprocket) wheels 59, 60 and up again, to the left and to the right of the vessel 10; an intermediate work-treating path of travel with runs down into, through, and up out of vessel 10, and up and down into and out of each of the wells 20, 21, 22; and a return path of travel connecting said loops of approach and recession above the vessel and the top structure 41.

In the well 10, the work will be initially cleaned of grease and dirt by the (hot) solvent. In the well 21, any dirty solvent clinging to the work will be rinsed off by the much purer and cooler condensed solvent supplied thereto from the condenser 27 and trough 28. Having been heated up in well 20 by the hot solvent and cooled off again considerably in well 21, the work will enter well 22 cooler than the vapor in the latter, which will therefore condense on the work and thus rinse it exceedingly clean of any last traces of grease. Ascending from the well 22, the work will dry off by the time it leaves the vessel 10.

The work to be treated and cleaned can be placed on the carriers 14 while the latter are at the loop of approach around wheel 59; and the cleaned work can be removed at the loop of recession around wheel 60. Preferably, the conveyor 11 will be (automatically) stopped (as above explained) with each carrier 14 in treating position near the bottom of each of wells 20, 21, 22, successively,—long enough each time for the solvent to act on the grease and dirt. Thus the travel of the conveyor 11 to carry each carrier 14 from one treating position to the next may be quite rapid,—much faster than would give adequate treating time in each well if the conveyor travelled uninterruptedly.

Having thus described my invention, I claim:

1. Apparatus of the character described, for treating things or work with volatile solvent whose vapor is heavier than air, comprising in combination an air-excluding treating vessel open at its upper portion for the introduction and removal of work, and provided with means affording in said vessel separate solvent wells, one for hot solvent, one, unheated, for liquid solvent con-

densate, and one for solvent vapor; means for heating and vaporizing liquid solvent in said hot solvent well, and thus supplying solvent vapor to said solvent vapor well; means above the wells for retaining and condensing the solvent vapor; and means for collecting the condensate and supplying it to said unheated well to the exclusion of the solvent vapor well.

2. Apparatus of the character described, for treating things or work therein with volatile solvent whose vapor is heavier than air, comprising in combination an air-excluding treating vessel open at its upper portion for the introduction and removal of work, and provided with means affording in said vessel separate wells for hot solvent, for condensed solvent, and for solvent vapor; a travelling conveyor for carrying work into treating position in each of said wells, one after another; means for automatically stopping the conveyor with a given piece of work carried thereby in each of said treating positions, one after another; means for heating and vaporizing liquid solvent in said hot solvent well, and thus supplying solvent vapor to said solvent vapor well; means above said wells for retaining and condensing the solvent vapor; and means for collecting the condensate and supplying it to said condensed solvent well to the exclusion of the solvent vapor well.

3. An apparatus of the character described for treating things or work with volatile solvent whose vapor is heavier than air, comprising in combination a framework including open side frames; an air-excluding treating vessel mounted in said framework substantially below its top and between said side frames, and open upward for the introduction and removal of work; an endless conveyor for carrying the work suspended therefrom, and means for operating said conveyor over a closed circuit with a return run and guide means therefor mounted on the side frames at the top of the frame, and with a primary course including upright approach and recession loops guided by means on the opposite ends of the frame beyond the ends of the vessel, extending down from upper guide means and up again substantially to the top of the frame, guide means mounted on the side frames at the top of the framework for the conveyor travel from and to said loops, and a work-treating path of travel between said latter guide means at opposite ends of the frame including runs downward and upward into and out of the open top of the vessel; and means for retaining solvent vapor in the vessel and preventing overflow thereof, including condensing means exposed to the vapor substantially below the top of the vessel for correspondingly drawing down the vapor level in the vessel.

CLARENCE F. DINLEY.
